Ms. 754

Sam'l B. H. Vance of New York, N.Y. Assign to Mitchell, Bailey & Co.
of State of Connecticut. — Letters Patent No. 754. Dated Jan. 1st 1856.

The schedule referred to in these Letters Patent and making part of the same.

To all whom it may concern:

Be it known that I, Samuel B. H. Vance, of the City County and state of New York, have invented an ornamental fixture which is intended as a chandelier, the configuration of which and the ornaments thereon constitute a new and original design, and I do hereby declare that the following is a full and exact description thereof reference being had to the accompanying drawings and to the letters of reference marked thereon, which make a part of this specification. —

My fixture is so constructed as to be easily modified and adapted

to the use of gas, oil, or any other illuminating material.

Fig. 1. is a view of the chandelier with three branched.

Fig. 2. is a top view of one of the chimney or glass holders.

In Fig. 1. A. is a socket upon the top of the column B. which may be screwed upon the gas pipe and by which the fixture is suspended. a. a. and B. B. are ornamental figures which are attached to and surround the column B. C. C. are turned ornaments near the bottom of the column B. there being one of these attached to the column horizontally and alternately with the rods of tubing D. D. D. C. is another turned ornament with leaves attached perpendicularly to the bottom of the column B. D. D. D. are three ornamental figures attached about midway to the tubing rods. E. E. are two of three elongated globes so united as to form a triangular base of the triangular column G.

This column and highly ornamented as shown in the drawing, and surrounded by drooping ornamental figures C. C. The rods of tubing terminate at the point where the elongated globes E. E. join to each other, immediately beneath each of which is an ornamental figure of leaves and a rosette as shown at F. attached to each of the elongated globes is an ornamental scroll-formed bracket or branch H. H. having each end ornamented with leaves as at K. K. the main body of which is further ornamented in bas-relief, all as shown in this figure.

On the outer end of each of the branches is affixed an ornamental glass or chimney holder I. I. At the bottom of the triangular base formed by the elongated globes is a turned ornament K. on the sides of which are affixed in a triangular form three ornamented scrolls L. L. alternating with which are smaller turned ornaments M. M. one of which is attached to each of the elongated globes, as shown in this figure.

Fig. 2. is a top view of the ornamented glass or chimney holder I.

What I claim as my invention and desire to secure by Letters

Patent is

The design configuration and arrangement of the several parts and ornaments as herein set forth forming a new and original design for a hall pendant or a chandelier with three branches and burners.

And Witnesses.

John P. Dickinson
Edmⁿ M. Johnson.

Sam'l B. H. Vance.
